(57) **CLAIM**

An ornamental design for a LED package, as shown and described herein.

DESCRIPTION

FIG. 1 is a perspective view of an LED package bearing the design.

FIG. 2 is a top view of the LED package.

FIG. 3 is a front view of the LED package.

FIG. 4 is a rear view of the LED package.

FIG. 5 is a bottom view of the LED package.

FIG. 6 is a left side view of the LED package; and,

FIG. 7 is a right side view of the LED package.

The structure shown as dome-shaped in FIGS. 1, 3, 4, 6, 7 is transparent.
